UNITED STATES PATENT OFFICE

2,549,509

KNOCKDOWN SHIPPING CONTAINER

Thomas Munroe, Dayton, Ohio, assignor to
 Moraine Box Company, Dayton, Ohio, a corporation of Michigan

Application June 8, 1945, Serial No. 598,371

4 Claims. (Cl. 217—12)

1

This invention relates to a box or shipping container, and more particularly to one of the so-called knock down type in which the ends, sides and top and bottom may be prefabricated, readily set up or assembled, readily fastened together in strong assembled shipping relation, and may be readily disassembled for reshipment or for reuse.

There have been some boxes or shipping containers or crates, in which the pieces of wood, and the reenforcing members to which they are nailed or otherwise attached are all interconnected, as in an automatic box machine, by wires or interlocking hinge members or the like so that they may be folded so that the parts will lie generally parallel to each other for shipment or storage before use. These may be pulled into proper relative position for use, an example being the well known orange crate. In general for boxes or shipping cartons of considerable size and to handle considerable weight in shipment, it has been the practice to nail the various parts of the box together in the well known manner.

While efforts have been made toward securing satisfactory knock down boxes or shipping containers of the size hereof and as a substitute for the well known built up boxes or containers, so far as I am aware no one has provided such a knock down box or shipping container nor one having the advantageous features and simplicity in manufacture and simplicity in use and reuse of the present invention.

The principal object of the present invention is to provide such a knock down box or shipping container having ends, sides and top and bottom each of which is a unitary piece or panel and which have provisions whereby the several parts may be readily assembled into shipping relation, and strongly held in such shipping relation, without the necessity of using nails, screws or the like to permanently affix the several constituent panels to each other.

Another object is to provide such a box in which the constituent parts have cooperating means permitting readily assembling of the panels and holding of them in position so that material to be shipped may be placed within a box and the final closure panel then put in proper place after which straps or wires bound tightly about the assembled parts will give requisite shipping strength and strong protection to the contents under rigorous conditions of actual use in shipment.

Another object of the invention is to provide prefabricated panel members, for such boxes or containers, each having means for cooperating with

2

another panel member, so that such panels may be readily assembled in desired relationship, and when tightly bound in such relationship the cooperating means will provide strong reinforcement against both external and internal bursting or disruptive forces.

Still another object of the invention is to provide such a box, and the constituent parts therefor, in which the parts of the box may be readily disassembled after shipment to facilitate removal of the contents by cutting or removing the straps or tying wires, and which permits of putting the panels and associated bracing and reinforcing parts in a compact, flat, packet for reshipment for reuse.

Another object of the invention is to provide comparatively light weight fabricated panels for assembly into a knock down box or shipping container, especially adapted for shipping comparatively large and bulky objects such as gasoline tanks for airplanes, which have cooperating means so that the box may be readily assembled about the object with the cooperating panels supporting each other in position and greatly strengthening the assembled box, with means for holding the parts in assembled relation, and which may be readily dismantled after use without damage to its component parts and returned for further service in a knock down condition which requires little shipping space.

Another object of the invention is to make a knock down box having prefabricated panels or walls free from projecting cleats or other devices when assembled which would decrease the usable inside size or space for contents of the box a substantial or objectionable amount or substantially increase the outside measurement or cubical shipping volume thereof; and also to provide such panels or wall members and cooperating strengthening members therefor which are effective for interconnection of such panels.

It is still another object of the invention to provide prefabricated parts for use as elements of and in the assembly of such a box, which parts are comparatively inexpensive of manufacture, which give great shipping strength when assembled and bound together for shipment, which may be readily disassembled for use, and which form a compact knock down package for reshipment for use.

Still another object of the invention is to provide a corner connection for the panels or wall members which is of particularly advantageous design and is formed from sheet metal by cutting and bending operations, and which assists in

assembling the panels and also in strengthening the corner of the box when assembled in position.

Another object is to provide aligning and strengthening lugs effective between panels for bracing the panels or wall members to give greatly increased strength to the box and which have means for permanent connection with one panel member and bracing connection with a receiving portion of a cooperating panel or side wall member.

In order to protect its contents during shipment a box or container, such as a shipping crate, must not yield at the joints or corner edges, and the sides must be strongly held against bursting or disruptive forces from within and from without. In the ordinary shipping case or crate this has heretofore been usually accomplished by nailing the boards, constituting the side and end and top members, together in more or less permanent relationship, and sometimes supplementing the strength of the nailed-together crate with metal tie bands or wires which are crimped or otherwise locked while bound tightly about the nailed crate to give additional strength. Although the desirability of a box having freely removable wall members has long been recognized, the requirements of strength, simplicity and low cost of manufacture and labor of assembly have been generally prohibitive, in commercial operations. In the present invention, however, a comparatively cheap prefabricated box, of unitary members readily assembled and disassembled for return and reuse is provided which also has adequate strength, even when built in sizes ranging up to a number of feet in each dimension.

In the drawing, in which a preferred embodiment of the invention is illustrated, and in which like numerals designate like parts in the several views,

Fig. 1 is an isometric view of a box or shipping container made up of constituent parts, in conformity with the preferred embodiment of this invention;

Fig. 2 is an exploded view through a corner, and part of two cooperating side and end panels, for such a box;

Fig. 3 is an inverted fragmentary view along the edge of a box panel showing the relative location of a lug and cooperating slot, the form of lug being that shown in Figs. 4, 5 and 6;

Fig. 4 is an elevational view showing a preferred form of lug;

Fig. 5 is an inverted plan view of the lug of Fig. 4;

Fig. 6 is a fragmentary view showing the face of a cleat and plywood sheet of a panel of the box and the arrangement of the lug receiving groove therein; and

Fig. 7 is a plan view of the metal blank from which the corner bracket shown in Fig. 2 is made, fold lines being shown dotted.

In the drawings, as an illustrative embodiment of the invention, there is shown in general a box of the type used for the protection of heavy or bulky objects such as gasoline tanks when they are shipped. The box is rectangular and is made up of panels which are readily assembled or detached for reuse and for knock down shipment but which when assembled and bound together form a construction of great strength for shipping.

The numeral 10 indicates generally the bottom of the box, the numeral 20 indicates generally the visible side wall of the box, the numeral 30 indicates generally the visible end wall of the box

and the numeral 40 indicates generally the top of the box.

The description of the construction of a side wall or panel of the box will be given first because that description will be generally applicable to the other side, end, top and bottom walls. This side wall has a reinforcing frame composed preferably of longitudinal upper and lower wooden members or cleats 21-22 and vertical wooden members 23, 24, 25 and 26 attached or fastened to a sheet of plywood or other suitable material 27 shown as 3-ply plywood by means of nails, staples, screws, glue, or the like to form a rectangular frame or panel. The cleats, bracing members and panel may be made of strength adequate for the size and intended use of the container. Such a prefabricated panel is of great strength and will withstand rigorous use.

Cut into the side of the panel member are a series of rabbets or grooves 28 which are suitably spaced from one another and from the corner of the panel to give adequate reinforcement and ease of assembly, a spacing of about two feet being satisfactory for articles such as the airplane fuel tanks referred to; but they may be spaced at such distances as to give the desired strength and resistance to internal and external disruptive forces when the box is in assembled relation and bound for shipment. In the plywood and cleat panel construction shown the rabbets or grooves are formed at one side of the cleat and the plywood forms one side of each such groove, as shown in Figs. 2 and 6. These grooves are of size, shape and location to receive the tongues or lugs of bracing members 15, in Figs. 1 and 2, formed of metal and of shape as shown in Fig. 2; or of shape as shown in Figs. 4, 5 and 6. These lugs are formed from plates and when struck up as shown at 16 and 94 the flat or flange parts 15 and 93 are attachable to the face of the panel in locations corresponding to the grooves in the edges of the cooperating panels. A similar groove construction 28 is formed in the upper longitudinal member or cleat 21 and similarly in each of the other panels, two opposite cleats of the end members 30, e. g., being designated 31, 32 and all the panels also having similar cleats and bracing members.

Each of the other side and end walls of the box is constructed in a manner similar to that of wall 20, so that when the box is assembled the lugs and cooperating grooves on the meeting edges of the walls or panels form a series of tongues and grooves whose spacing and relation is such that the parts will stay assembled for packing and when properly bound are adequately held against internal and external disruptive forces. As shown in Figs. 2 and 6, the ends of the rabbets or grooves are preferably curved as at 28', these curves being so calculated with respect to the size of the tongue that they serve as directing faces to facilitate aligning of the parts in assembling the panels and as limits which prevent longitudinal displacement when assembled.

The bottom and top panels 10 and 40 also have longitudinal frame members or cleats 11 and transverse cleat members 12 similar to those described above which are likewise affixed to the inner plywood sheet 13 upon which the edges of the four side panels of the box rest when it is assembled; and as shown the lugs are attached thereto and to the cleats as by means of nails 14, which nails pass through the lugs to fasten the lugs in position. The projecting portions 16 are shaped and so formed as to have such

dimensions that they will fit into and cooperate with the grooves 28 to prevent displacement of the sides and ends of the box in the manner which has been hereinbefore indicated. When emplaced, there is preferably a snug fit between the lug 16 and the groove 28. This same relationship exists with respect to the form of lug members 90—94 and the grooves into which they fit.

For greater ease in assembling and packing the corners of the box are held in fixed relation to each other by angle brackets which are indicated generally by the numeral 50. These brackets may be conveniently made from a metal plate 51 (Fig. 7) the shape of which, before forming into the angle brackets, can best be comprehended by an inspection of that figure. The outlines of that figure are indicated by the numerals 52 to 61, the lines 57 and 58 being shown at an angle of approximately 90° to each other and at an angle of 45° to the line 52. In forming the angle bracket from this plate the plate is cut on the lines *a* and *b*, and may be readily folded into the interrelationship of the parts by folding up at right angles on the dotted lines *e* and *i* to form flanges 68 and 69. Dotted lines are used in Fig. 7 to indicate fold lines. The section bounded by the lines 59 and 60 is now folded down at right angles on the line *c*, and the section having the outline 61 is folded upward at right angles about line *d*. The section having the outlines 56 and 55 is then folded upward at right angles on the line *g* and the section having the outline 52 is folded up at right angles about the line *f*. The foregoing folds having been completed, a final right angle fold is made on the line *j*, which brings the part having the outlines 59, 60 in overlapping relation to the part having the outlines 55, 56, the overlapped parts of which are welded or otherwise firmly attached to each other, producing the bracket shown in Fig. 2. The edges 55 and 61 may be overturned slightly if desired to form cam faces to assist in entering and seating the panels in the angle channels thus produced.

The bracket as thus made and as shown in Fig. 2 has a base 62, 63 which is angle shaped and forms the bottom of a right angle channel each of which brackets receives the corner of two adjacent assembled panels of the box. This channel has inner right angle walls or flanges 64, 65 and outer right angle walls or flanges 66, 67. On the outer wall of the channel 66, 67, at the ends thereof are the inturned flanges 68, 69 which are equidistant from the external corner of the angle fitting and so as to fit in slots 70, 71 which are cut in the sides of the box panels at equal distances from the corner of the box. By this arrangement the angle brackets are interchangeable with any panel having the dimensions and the proper location of slots 70, 71. Likewise the lugs are interchangeable and therefore they may be made in quantity production and used with any prefabricated panels having grooves of dimensions and spacing to match them.

With the walls of the box made with properly located spacing and bracing elements 15 and with grooves correspondingly located in the edges of abutting wall or panel sections the fitting of the grooves over the lugs of the bracing plates will locate the parts in proper relation. In assembling the box the side wall panels are brought together as shown in the upper portion of Fig. 2 and the corner brackets, having been made from the blanks in the manner described, are slid over the corners of adjacent walls (Fig. 2) so that the

flanges 68, 69 fit into the slots 70, 71 and hold the corners in fixed relation to each other. It will be understood that such brackets are fitted over the eight corners of the box, forming a rectangular wall whose sides cannot be displaced without removing the brackets, and with the side and end wall panels also positioned with the lugs on the bottom 10 located in the grooves in the cooperating edges of the side and end panels, and the adjacent vertical edges of the side and end panels likewise so positioned the box will stay assembled and may be readily packed. When so assembled and packed the top can then be emplaced and the walls of the crate and top will thus be held in fixed relation by the angle members 50 and by the lugs and grooves, and thus constitutes a construction so assembled capable of resisting considerable external as well as internal pressures. The entire box, with its contents, is now bound by metal or other straps 80 which hold the parts in assembled relationship. By making these straps suitably strong to hold the panels in assembled, packed, relation a strong, light, prefabricated box is formed which has great resistance to internal and external disruptive forces and which has been found quite satisfactory in use. Furthermore when the box has served its purpose and is to be unloaded the straps 80 are removed and the box readily dismantled. And the panels may be readily dismantled without injury to them, the six panels readily separating when the corner angles are removed and the disassembling readily accomplished in reverse order to the assembling. They can then be tied together in a flat group, and returned for further and similar use, requiring little shipping space for this purpose, the angles being placed in a bag or otherwise attached to the return package.

An exceptionally efficient and strong form of spacing and bracing lug is shown in Figs. 3, 4, 5, having a metal plate 90 having nail holes 91 through which nails 92 may be used to attach it to a box wall, the overturned ends of the nails being shown in Fig. 3 at 92, and a curved projection 94 satisfactorily formed by stamping to proper shape and size, as shown. This form of the device is believed generally preferable to the form 15 which is shown in Fig. 2. It has no sharp edges on the projecting lug part 94 which might cut the hands of workmen or the surfaces of the cooperating grooves. The curved ends of the lug serve as directing surfaces to seat panels having grooves with straight ends as well as those having cammed ends.

Among the advantages of the invention are these, that a knock down box is made which has sufficient strength for ordinary rough usage in shipment without permanent fastenings such as nails driven through abutting faces of different wall members, as has heretofore been the usual practice. Without such nails the box forms a strong shipping construction which is also capable of easy dismantling and repeated use. Another particular advantage of the invention is that in dismantling the box it is not necessary to use tools on the box itself but only to remove binding strips and it is thus not necessary to tear the box apart, in whole or in part, before unloading, with resulting destruction of or damage to the box after a single use. This box overcomes such difficulty and makes it practicable to reuse boxes for a number of shipments, and even when a panel member of the box is damaged or destroyed, it is not necessary to replace the whole box but merely to substitute a new member which is

standard and can be purchased from the maker of the box, which is true also of the strong and stiff angle bracing members 50 and the lugs 15 and 90.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In a knock down box of the character described comprising detachably connected walls each formed by a single panel, metal plates mounted on certain of said wall panels and having lugs projecting at right angles therefrom along a substantial longitudinal extent thereof, grooves formed in the edges of cooperating panels to receive said projecting lugs, corner brackets having angularly arranged channels to receive adjacent wall panels of the box by relative movement substantially parallel to the abutting edge of said wall panels, slots in said wall panels adjacent the corner and cooperating with flanges on the corner brackets to prevent disengagement of said panels by relative movement at an angle to said abutting panel edges, and means to hold the box parts in assembled relation for shipment.

2. In a knock down box of the character described comprising walls each formed by a single panel, spaced metal plates on certain of said panels having lugs projecting at right angles thereto and along a substantial longitudinal extent thereof, the edges of other panels having correspondingly spaced grooves therein to receive said lugs to give aligning and bracing connection between cooperating panels, cam surfaces to aid in aligning said grooves and lugs and causing them to interfit to give proper relative location of cooperating panels and to strengthen the box against disruptive internal and external forces, corner brackets having angularly arranged channels to receive adjacent panels of the box upon relative movement substantially parallel to the abutting edges of said adjacent panels, slots in the panels, flanges on the corner brackets cooperating with said slots to prevent disengagement of said panels by relative movement at an angle to the abutting edges thereof, and means to hold the box panels in assembled relation, said cooperating lugs and grooves and said corner brackets being constructed for detachably holding the panels firmly together without decreasing the effective packing space inside the box or increasing the external dimensions of the box.

3. In a knock down box of the character described having walls each formed by a panel adapted to be detachably assembled to form the

box, the combination of a lug member comprising an attaching plate having a lug struck up therefrom along a substantial longitudinal extent thereof materially in excess of the thickness of said panel, means for attaching said lug member against the face of one of said panels with said lug extending substantially perpendicularly to said face, another of said panels having a longitudinally extending groove in an edge thereof proportioned to receive said lug therein, cooperating cam surfaces at the ends of said lug and groove respectively for aligning said lug and groove in interfitting relation upon assembly of said panels, and means for detachably retaining said panels in assembled relation with said lug interfitting with said groove.

4. In a knock down box of the character described having walls each formed by a panel adapted to be detachably assembled to form the box, the combination of spaced metal plates on the faces of certain of said panels having lugs projecting at right angles therefrom along a substantial longitudinal extent thereof, the edges of others of said panels having correspondingly spaced grooves therein for receiving said lugs to form a braced connection between said panels, said lugs and said grooves being complementarily curved substantially about a radius arranged transversely of the length thereof adjacent their respective ends to provide cooperating cam surfaces at the ends of said lugs and grooves for aligning said lugs and grooves in interfitting relation upon assembly of said panels, and removable means for holding said panels in said assembled relation providing for ready disassembly thereof.
